UNITED STATES PATENT OFFICE

JOSEPH G. MENZER AND HARRY E. KHOURY, OF NEW BEDFORD, MASSACHUSETTS, ASSIGNORS TO KHOURY WARP STOP MOTION, INC., OF NEW BEDFORD, MASSACHUSETTS, A CORPORATION OF MASSACHUSETTS

WARP STOP MOTION

Application filed January 27, 1928. Serial No. 249,960.

The present invention relates to warp stop motions for looms, and although the invention is not restricted to a specific type of stop motion, it is intended primarily for use in connection with that type wherein the harness or shed forming heddles perform the additional function of detector wires which serve to stop the loom whenever one of the warp threads breaks or drops.

Stop motions of this type are broadly old, and are illustrated, for example, in my Patents Nos. 1,527,195 and 1,527,196, granted Feb. 24, 1925.

An object of the invention is to provide a stop motion which is simple in construction, and requires little or no adjustment throughout extended periods of operation, and which, because of its simplicity of construction, is accurate and positive in operation, and may be readily applied to a loom.

A further object of the invention is to provide a mechanism which may be readily applied to a loom, irrespective of the number of its harnesses or harness frames.

One objection to stop motions, which include a detector element having a detecting movement as the harness frames rise and fall, is that it is necessary to provide an accurate timing of the engagement of the various parts which impart the detecting movement to the bar, so that the bar is rocked at exactly the proper position of the harness frame, and is released for rocking movement in the reverse direction at exactly the proper point, whereby the detector bar will not be locked except by heddles which have fallen.

One object of the present invention is to provide a construction in which the dwell of the locking position of the detector bar is practically fixed by the moving contact parts which move the detector bar to the locking position and in which the contact parts are separated by other means than the upward movement of the harness frame so that the detector bar can move back to unlocked position when not engaged during its detecting movement by a fallen heddle.

The present invention seeks to provide a

construction which will operate as desired without the necessity for adjusting the parts frequently to maintain an exact timing in the operation of its various parts.

Furthermore, the invention seeks to accomplish these objects with a construction which is simpler, and hence more economical to install and operate than devices which have heretofore been developed.

These and other objects of a similar nature will become apparent as the description proceeds in connection with a preferred embodiment shown in the accompanying drawings, wherein:

Figure 1 is a side elevational view with the mechanism shown as applied to a two-harness loom, the frame and lay of which are shown in dotted lines.

Figure 2 is a fragmentary front elevational view showing the relation of a harness frame to the parts which are engaged to rock the detector bar, and effect stopping of the loom.

Figure 3 is a fragmentary side elevational view of the parts which are mounted upon the loom frame.

Figure 14 is a fragmentary elevational view taken from the opposite side of the heddle frame shown in Figure 11, showing the lowermost position of the contact finger.

Figure 15 is a top plan view of the top contact mechanism shown in Figure 2, and

Figure 16 is a fragmentary view showing a modified form of means for actuating the lower contact support.

Referring to the drawings, and more particularly to Figures 1, 2 and 3, 10 indicates diagrammatically a side frame of a loom having the usual upstanding arm 10', supporting by the straps 11, the heddle frame 12.

The heddle frames, one of which is partially illustrated in Figures 2 and 6, are of the usual rectangular formation, having upper and lower cross pieces 13 connected by vertically disposed side pieces 14, which, intermediate their ends, receive upper and lower pairs of cross bars 15. These cross bars are held against longitudinal movement by means of wire retainers having portions 15' which extend into the side pieces 14, and ends 16 which are angularly bent and extend through transverse openings in the projecting ends of the bars 15. In each heddle frame there is mounted, preferably above the upper pair of cross bars 15, a pair of detector bars 17, the number of detector bars depending, of course, upon the number of banks of heddles arranged within the frame. As shown clearly in Figure 10, each detector bar between its ends is non-circular in cross section, having longitudinally cut away portions which form a rib 18. The heddle openings 19, through which the detector bars extend, are formed to permit free rocking movement of the bars when the warp threads are unbroken, but are adapted to lock the bar against such movement whenever one of the warp threads breaks. For this purpose, the slots 19 in the heddles are reduced, as indicated at 20, to receive the rib 18 upon the detector bar, and, as will be understood, whenever one of the warp threads breaks or drops, its heddle will also drop, causing the rib 18, which is moved to vertically disposed position as the detector bar is rocked, to fit within the reduced portion 20 of the heddle slot, whereupon the detector bar will be held against rocking movement, and through suitable mechanism as the heddle frame moves, will effect stoppage of the loom.

The mechanism thus far described is broadly old, and is disclosed and described more fully in my patents above referred to.

The present invention relates to certain other features of related and cooperating structure which will now be described.

Each detector bar, as is customary in structures of this character, is normally held yieldingly with its rib 18 in the angularly disposed position with respect to the vertical, as illustrated in Figure 10. In the present instance, the yielding means for retaining the detector bars in this position comprises sleeves 22 each carrying a pair of short arms 21, 21', the sleeves being fixedly secured to the bars as by cotter pins 23. A connecting link 24 has its ends extending into a transverse opening in and adjacent the ends 25 of arms 21 and 21'. An open end of each pin is interiorly threaded and receives a set screw 26' which is adapted to engage the link 24 within the pin and thus retain the link in any position it is adjusted through the opening in the pin. This construction permits an adjustment of the two detector bars so that the ribs 18 thereof may be set in exactly the proper position at one extreme of their movement to align with the recess 20 in the heddles. To make this adjustment, it is simply necessary to loosen the screws 26' and then to lock the detector bars by a heddle. When locked in this position, the set screws 26' will be adjusted to clamp the link 24. There is thus provided a relatively simple adjustment which may be readily made.

A spring 27 has its upper end 28 anchored to the heddle frame and extends downwardly so that its lower end passes the inner end of one of the pins 26 and thus presses the arms 21, 21' toward the right, as viewed in Figure 8.

At the opposite side of the heddle frame, one of the detector bars carries a sleeve 30, which is secured thereto as by means of a pin 31 (Fig. 6a) projecting through aligned openings 31' in the bar and sleeve, wherein it is retained by a spring pressed lever 29 pivoted at 29' upon the sleeve 30, the pin being attached to the lever so that when its opposite end 29'' is pressed the pin will be withdrawn from the opening in the detector bar and thus permit the sleeve to be removed from the bar as is sometimes desirable, for instance, to remove some of the heddles or to add others.

The sleeve has a portion projecting beyond the end of the detector bar and which is transversely grooved to receive an engaging or contact finger 32 mounted upon a pivot pin 33 extending transversely of the rod. The pin 33 provides a pivotal axis for the finger 32, the axis extending at a right angle to the axis of detecting or rocking movement of the detector bar within the frame.

Adjacent the pivot pin 33, the finger is

laterally deflected as at 34, (Fig. 7) so that the projecting portion thereof is laterally offset with respect to the rocking axis of the detector bar 17. The finger normally tends 5 to gravitate toward the downwardly inclined position illustrated in Figure 6, and has a rearwardly extending portion 36 extending adjacent a block 37 having an under or bottom abutment face 38, and an inclined side 10 39 which permits the finger to drop downwardly as soon as the detector bar has rocked sufficiently to carry the portion 36 of the finger from beneath the relatively narrow under-face 38. When the downwardly inclined portion 32 of the finger is 15 lifted by means which will be later described, the pressure on the under-face thereof tends to rock the bar to carry the rib 18 thereof to a vertical position, this rocking movement of the bar which results from pressure on the under-edge of the finger 32 being due to the laterally offset position of the portion 32 of the finger with respect to the axis of the bar, as illustrated in Figure 7.

The rocking movement of the bar carries the portion 36 of the lifted finger beneath the block 37, and thus the finger is held in the substantially horizontal position illustrated in dotted lines in Figure 6.

As will be understood, rocking movement of the detector bar, upon which finger 32 is mounted, will also rock the adjacent detector bar through the link connection 24 (Figure 8) and rocking movement of the two bars is limited by means of a stop pin 40 extending downwardly through the block 37 and held in position by a set screw 41. The lower end of this stop pin fits within 40 a groove 42 in the sleeve 30, and its engagement with the end of the groove upon rocking movement of the sleeve and detector bar prevents rocking movement beyond the dotted line position of the finger indicated in 45 Fig. 6.

As in the usual stop motion of this type, should there be a fallen heddle within the frame due to a sagging or broken warp thread, when the detector bar is rocked, the narrow portion 20 of the heddle will receive the rib 18 upon the detector bar and prevent the same from rocking in a counter-clockwise direction under the tension of spring 27 which is tensioned as the bar is rocked by upward pressure on finger 32. On the other hand, should there be no fallen heddle, the detector bar will be rocked in a counter-clockwise direction under the influence of spring 27 which has been previously tensioned, and such rocking movement in the counter-clockwise direction will carry the finger portion 36 from beneath the block 37, and permit the finger to drop to the position illustrated in Figure 6.

65 Referring to the means for imparting a

detecting or rocking movement to the detector bar, the same preferably is independent of the harnesses and is mounted upon the loom frame.

Referring more particularly to Figures 1, 2 and 3, a supporting and guide block 43 is fixedly mounted upon a horizontally extending rod 44 carried at one end by a bracket block 45, into which the rod 44 extends, being held therein by means of a set screw 46. The block 45 has an elongated opening 47 therein to receive a securing bolt 48 by means of which it is fixedly attached to the loom frame 10.

The opposite end of the rod 44 extends through the block 43 which is held against movement on the rod by means of a set screw 49. The block 43 has a vertically disposed guide opening through which slidably extends a vertical rod 50, which at its lower end, is pivotally secured by means of a pin 51 to a forked lug 52 upon a horizontal arm 53. The arm 53 extends into a block 55 and the latter is pivoted to the loom frame by means of a bolt 54. The end of the arm 53 80 has a finger 56, the under-surface 57 of which is curved upwardly from a point 58 spaced from its end 58. The arm 53 and finger 55 rest upon and are supported by a member 59, carried by a moving part of the 85 loom, which in the present instance, for purposes of explanation only, is located on the lay. As the pin 59 moves with the operation of the loom lay, the arm 53, which is supported at its free end thereby, moves upwardly and downwardly about the bolt 54 90 as a pivot, and through the pivotal connection 51 with the vertical rod 50, the latter is vertically reciprocated in the guide block 43.

In Figure 16, there is shown a modified arrangement for vertically reciprocating the rod 50. Referring to Figure 16, the rod 50 is extended downwardly and connected to a lever 53' pivoted at 54'. The lever 53' rests upon a cam 59' which is employed instead of the pin 59 illustrated in Figure 1. The cam 59' is mounted upon a continuously driven shaft 59" which may be the cam shaft of the loom. As will be understood, rotation of shaft 59" will cause the cam 59' to raise 100 and lower the lever 53' and thus actuate rod 50 in substantially the same manner as the pin 59 causes the arm 53 (Figure 1) to rise and fall. This construction will sometimes be found preferable, since in the construction first described, the movement of the rod 50 is dependent upon movement of the lay. The formation of the cam permits the rod 50 and the contact 60 associated therewith to be moved differently when the lay is going in 105 than when it is going out, which is desirable, for instance, when weaving artificial silk. With the cam 59' it is possible to arrange for the position of the lower contact 60 when the lay is going in than when it is going out. 110 115 120 125 130

The rod 50 carries a contact element 60, which has a depending end portion 60' to prevent the contact finger 32 from moving beneath the horizontal portion 60, and is carried at the outer end of an arm 60''. The contact element is adjustable longitudinally of the arm, being held in any selected position by means of a set screw 61 extending into the contact element against arm 60'' which projects through the contact element. The inner end of the arm 60'' is enlarged to form a pair of shoulders 62, which abut upon upstanding lugs 63 upon a supporting collar 64 loosely fitted on the rod 50 because of its enlarged bore 64' and supported by a collar 65 secured to the rod 50 by set screw 65'. The collar 65 has a V-shaped seat 65'' in its top surface (Fig. 4^a) which receives a depending projection 64'' on collar 64 and this supports the latter with the contact arm 60'' and contact 60 for lateral movement on rod 50, the purpose of which will be later described.

As will be observed, the arm 60'' is forked 25 (Fig. 4) to straddle the rod 50. A coil spring 66, abutting a collar 67 at its upper end, presses a washer 68 downwardly against the upper surface of the arm 60'', and thus maintains the arm upon the collar 64 and in 30 substantially horizontal position. The arm 60'' has a depending lug 69, which fits within a vertically disposed groove 70 in the face of the collar, and, as will be observed (Figure 2) its rear edge is spaced from the 35 inner face of this groove so that downward pressure upon the contact element will, if in excess of the tension of spring 66, depress the arm and contact element until stopped by engagement of lug 69 with collar 64. Thus the contact element serves as a yielding 40 abutment for the finger 32 as the harness rises and falls.

As above explained, the contact element with the supporting arm 60'' and collar 64 are mounted on rod 50 so that a lateral movement is possible. This lateral movement is obtained through the provision of the enlarged bore in collar 64 and the resting of the latter on collar 65 through the 50 V-shaped seat in the latter and the V-shaped bearing member on the collar 64 (Fig. 4^a). Obviously pressure applied horizontally on the end of the contact element 60, as by engagement of the lay therewith, will swing 55 the arm 60'' and rotate collar 64 causing the V-projection 64'' thereof to ride up the side of its seat 65'' at the same time tensioning spring 66 which will return the arm and collar to their normal position when the 60 pressure is relieved. This arrangement is desirable for various reasons, particularly in view of the fact that in many installations there is danger that the lay, as it moves toward the heddle frames will engage 65 the end of the contact member 60, and un-

less the latter yields laterally there is danger of breakage as well as the danger that the hand of the operator, which frequently rests on top of the lay, will be caught between the lay and the end of the contact 70 element 60.

The arm 53, upon which rod 50 and contact element are supported, as has been explained, is movably mounted, having its free end upheld by the pin 59 upon the lay. 75 The arm is arranged so that as the finger 32 upon the harness frame engages the contact element 60 as the harness frame drops and the finger is thus raised to impart a rocking detecting movement to the detector bar, the contact element 60 will be substantially stationary. This stationary 80 position of the contact element is provided for by arranging the pin 59 and finger 56 on arm 53, so that the pin travels from adjacent the free end of the finger 56 along the substantially horizontal portion of the under edge of the finger during the rocking of the detector bar by engagement of its contact finger 32 with the contact element 60. 85 However, substantially immediately following the rocking of the detector bar, the pin 59 begins to travel from the point 58 along the upwardly inclined portion of the under surface of finger 56, and thus permits or causes the arm 53, with its rod 50 and the contact element, to drop to the dotted line position illustrated in Figure 3. This floating or moving support for the contact 90 59, which maintains it stationary 100 until the detector bar has been given its full rocking movement, but hastens the separation of the contact element and finger on the detector bar by positively moving the contact element away from the detector 105 bar immediately following the detecting movement, insures that the detector bar will be free to return to its normal position before the harness frame has risen enough to allow the heddles to rest on the detector 110 bar. In constructions which have heretofore been developed, it has been customary to rely upon the upward movement of the harness frame to disengage the elements which have rocked the detector bar, and in 115 case of defective adjustment, the loom is frequently stopped, due to the fact that the separation of the engaging elements is not sufficiently instantaneous. Moreover, in 120 stop motions of this character, due to the association of the detector bar with the heddle frame, it has been found that the time of movement of the detector bar varies due to changes of the harness frame. The harness frame is ordinarily supported on straps 125 of flexible material and is subject to a swaying motion, the extent of which depends on how tight the straps hold the frame. The straps stretch, and as they do the frame will drop lower and also sway. As the 130

harness straps lengthen, the harness frame has a longer movement, and thus an ever increasing pressure is exerted upon the detector bar unless some means is provided to 5 terminate at a fixed and invariable time the pressure upon the detector bar which gives it its detecting movement. In constructions heretofore provided, the pressure has been exerted upon the detector bar until the heddle frame rises, but in the present construction, due to the floating or moving support for the stationary contact element, the latter will relieve the detector bar of moving pressure as soon as the detecting movement 10 of the bar has been completed, and thus there is provided a constant or invariable movement of the detector bar regardless of the length of movement of the heddle frame. Moreover, by providing a floating or moving support for the contact element, and which, as described, positively moves the contact element on the loom frame away from the bar in the harness following the detecting movement of the detector bar, such exact or nice adjustments 15 are unnecessary.

Thus far there has been described the construction of the harness frame and the detector bar, and the means for imparting to 20 the detector bar its detecting movement.

Reference will now be made to the mechanism for stopping the loom when the detector bar is locked by a fallen heddle against return movement under the influence 25 of return spring 27 and the finger in the horizontal locked position shown by the dotted lines of Figure 6.

The supporting and guide block 43 upon rod 44 receives the lower end of a vertically disposed supporting rod 71, which is held in vertically adjusted position by means of a set screw 72. The upper end of this rod carries a pin 73, which is pivoted in the rod and carries a lever 74, having at its outer end and positioned directly above the contact finger 32 on the harness frame a horizontally disposed contact element 75 which is arranged upon an arm 76. The arm 76 is pivotally carried by means of pin 77 at one end of the lever 74, which has an abutment shoulder 78 arranged to coact with the curved end 79 of arm 76 to permit the latter to pivot laterally in one direction, indicated by the arrow 80, on pin 77; the lateral movement is normally opposed by a spring 80' which bears against the side of arm 76. This lateral movement of the contact element 75 and its arm 76 is provided for the same reason as the lateral movement of the lower contact element, namely, to avoid breakage or danger to the operator in the event that the lay engages the end of the contact element.

The rear end of lever 74 carries a depending link 81' which at its lower end extends

through a laterally projecting pin 81" pivotally mounted on a dagger 81. The dagger is pivotally mounted at 82 upon a lug 83 fixed by means of a set screw 84 upon a slide rod 85, the free end of which, at 86, is connected to an operating fork 87 for the shipper lever 88. The dagger is normally maintained or supported in the horizontal position indicated in Fig. 1 by means of a collar or nut 82' on link 81' so that it will be normally out of the path of a dagger engaging member 89 which in the present instance is located upon the loom lay, although obviously, it may be located upon any other moving part of the loom. As 75 will be understood so long as the dagger is supported in the position illustrated in Fig. 1 with its forward end out of the path of the pin 89, the operation of the loom will continue. But should the link 81' lower its 80 dagger supporting collar 82' the rear end of the latter will gravitate downwardly and its forward end 82" will move upwardly 85 into the path of the pin 89 on the loom lay, which, upon engagement with the dagger 90 will actuate the latter and the slide rod 85 to move the shipper lever. The slip connection between the link 81' and the dagger permits the link to move variable distances, while at the same time providing a 95 constant range of movement of the dagger. This is an important feature of the construction, since sometimes after considerable use, the heddle frame may lift a distance much greater than that originally contemplated, and in such event the upper contact, as well as the link 81', will be moved a proportionately greater distance. Due, however, to the slip connection between the link and the dagger, the movement of the 100 latter will be a constant one regardless of variations in movement of the upper contact. As will be understood, the link 81' will be moved downwardly only when the contact finger 32 upon the heddle frame is held in horizontal position through locking of the detector bar by a fallen heddle and is thus caused to engage the contact elements 105 75 when the heddle frame moves upwardly.

Referring to Figures 11 to 14, there is shown a modified harness frame construction, having a slightly different form of mechanism for cooperating with contact elements which impart a detecting movement to the detector bar, and also stop the loom 115 when the detector bar is locked by a fallen heddle. This form of mechanism is illustrated as applied to a heddle having a single detector bar 90, with the usual rib 91 for engagement with the narrow portion of the 120 heddle slot, and mounted at its ends in the harness frame. A spring 92 at one side of the frame tends to urge the rocking bar to one extreme of its movement, which is limited by a stop finger 93 extending into 125 130

a groove 94 upon a collar 95 fixed to the detector bar, the spring 92 also extending into the same groove.

At the opposite side of the heddle frame, 5 the detector bar carries a collar 96, having a cam surface 97 engaging a cam 98 which is pivoted at 99 upon a bracket 100, the axis 99, as will be observed, extending at a right angle to the axis about which the detector 10 bar rocks. The cam 98 has an outwardly extending contact finger 101, which is normally maintained in the substantially horizontal position illustrated in Figures 11 and 14 by means of a spring 102 anchored at 103 15 to the harness frame, and at 104 secured to the cam 98. When the under edge of the finger 101 engages, as the harness frame is lowered, a suitable contact element independent of the harness, such as the contact 20 160 illustrated in Figure 1, which may be fixedly mounted on the loom frame, the finger will be raised as it moves downwardly past the contact as indicated by the arrow in Figure 11, and through engagement of the 25 cam 98 with cam surface 97, will rock the detector bar to carry the rib 91 thereon into vertical position to receive any heddle which may have fallen. As the finger 101 moves upward past the contact 160, Figure 14, it 30 will yield downwardly and tension spring 102 which will return it when it has moved past contact 160 to the position in Figure 11.

The collar 96 upon the rock bar, has a second cam surface 105 adapted to cooperate 35 with a toe 106 upon the lower end of a lever 107, which is pivoted at 108 on a bracket 109 fixedly secured to the loom frame. A leaf spring 110 bears upon a pin 111 on the lever 107, and normally urges the same to its substantially vertical position illustrated 40 in Fig. 11, but upon actuating of the detector bar and its collar 96, the cam surface 105 engages the toe 106 and moves the lever outwardly away from the harness frame in 45 which an outwardly extending arm 112 thereon is carried to a position beneath a second contact element which may be engaged upon upward movement of the harness frame, a suitable contact element being 50 shown, for instance, at 75 in Figure 2. As will be understood, in the event the detector bar is not locked by a fallen heddle when it is rocked through the operation of cam 98 and its finger 101, it will be returned to 55 its normal position by means of spring 92, which has been tensioned through the clockwise movement of the detector bar (Figure 13) and at the same time, the lever 107 will 60 be drawn inwardly by leaf spring 110, which is tensioned upon outward movement of the lever away from the harness frame.

This form of construction is distinguished 65 from the construction illustrated in Figures 1, 2 and 3, essentially in that there are provided two separate elements, namely, the

finger 101 and lever 107 for engaging, respectively, (1) the contact element 160 which imparts the detecting movement to the detector bar, and (2) the contact element 75 which is engaged to stop the loom when the 70 detector bar is locked by a fallen heddle. Furthermore, it will be observed that these 75 engaging elements 101 and 112 upon the harness frame, are not mounted directly upon the detector bar, as in the form previously described, but are supported upon brackets on the harness frame independently of the detector bar. Moreover, the finger 101 is adapted to cooperate with a fixed contact 80 instead of the floatingly supported contact 60 of Figure 3.

It will be noted that in this form, provision is made for quick release or quick disengagement with the contact elements 101 and 160 by moving the contact 101 downwardly past the fixed contact 160 as the heddle frame moves. As soon as the finger 101 passes contact 160 when moving in the direction indicated by the arrow in Figure 11, the detector bar will be free to move under the influence of spring 92 unless it has been locked by a fallen heddle. As the harness frame moves upwardly to carry finger 101 past contact 160 (Figure 14), the movement downwardly of finger 101 will 90 not affect, by its engagement with the contact, the detector bar, since the cam 98 is free for outward movement away from the cam 96 on the detector bar.

As this device cooperates with the remainder of the stop motion in the manner described in connection with the form of Figures 1 to 10 inclusive, it is thought that 100 no further description is necessary.

Obviously, numerous modifications may 105 be made in the structure illustrated, and which has been described in detail, and the invention is not limited to details of construction, but includes all modifications 110 which are within the spirit of the following claims.

We claim:

1. In a warp stop motion for looms, and in combination with the heddle frame and its shed forming heddles, a detector bar having a detecting movement in one direction in said frame, movable means carried by said frame adapted upon movement to impart a detecting movement to said bar, 115 contact means mounted on the loom adapted to be engaged by said first mentioned means as the heddle frame moves downwardly and to actuate the latter whereby to give said bar its detecting movement, means for automatically moving said bar in the opposite direction upon disengagement of said contact means and said means on the loom frame, and means other than the upward movement 120 of the harness frame permitting disengage- 125

ment of said movable means and said contact means on the loom.

2. In a warp stop motion for looms, and in combination with the heddle frame and its shed forming heddles, a detector bar having a detecting movement in one direction in said frame, movable means carried by said frame adapted upon movement to impart a detecting movement to said bar, contact means mounted on the loom adapted to be engaged by said first mentioned means as the heddle frame moves downwardly and to actuate the latter whereby to give said bar its detecting movement, yielding means carried on the harness frame for automatically moving said bar in the opposite direction upon disengagement of said contact means and said means on the loom frame, and means other than the upward movement of the harness frame permitting disengagement of said movable means and said contact means on the loom.

3. In a warp stop motion for looms, the combination with a vertically and bodily movable detector bar, of means to impart a detecting motion to said bar as it moves vertically in one direction, and means for freeing said detector bar of said first mentioned means by movement of the latter away from the bar substantially immediately following its detecting movement and before the bar has moved substantially in the other vertical direction.

4. In a warp stop motion for looms, the combination with a vertically and bodily movable detector bar, of means engageable to impart a detecting motion to said bar as it moves vertically in one direction, and means independent of the loom lay for moving said first mentioned means away from said detector bar substantially immediately following its detecting movement and before the bar has moved substantially in the other vertical direction.

5. In a warp stop motion for looms, the combination with a heddle frame having a series of heddles, of a substantially horizontally disposed detector bar movable with said frame and having a detecting movement thereon, contact means engageable as the heddle frame moves vertically in one direction to give said bar a detecting movement, and means for moving said contact means away from said bar substantially immediately following said detecting movement and before the heddle frame has moved substantially in the opposite vertical direction, whereby disengagement of the detecting means and the bar is effected substantially independent of the vertical movement of the heddle frame.

6. In a warp stop motion for looms, the combination with a heddle frame having a series of heddles, of a substantially horizontally disposed detector bar movable with said

frame and having a detecting movement therein, a contact element positioned beside said frame, means carried by said frame for engaging said contact element and adapted upon engagement therewith to impart a detecting movement to said bar, and means for causing said contact element to move away from said first mentioned means substantially immediately following said detecting movement, said first mentioned means upon the frame being mounted for pivotal movement about an axis extending at an angle to the axis of detecting movement of the bar.

7. In a warp stop motion for looms, the combination with a heddle frame having a series of heddles, of a substantially horizontally disposed detector bar movable with said frame and having a detecting movement thereon, a contact element positioned beside said frame, means carried by said frame for engaging said contact element and adapted upon engagement therewith to impart a detecting movement to said bar, and means for causing said contact element to move away from said first mentioned means substantially immediately following said detecting movement, said first mentioned means upon the frame having pivotal movement independent of the detector bar and about an axis other than the axis of detecting movement of the bar.

8. In a warp stop motion for looms, the combination with a heddle frame having a series of heddles, of a substantially horizontally disposed detector bar movable with said frame and having a detecting movement thereon, a contact element positioned beside said frame, means carried by said frame for engaging said contact element and adapted upon engagement therewith to impart a detecting movement to said bar, and means for causing said contact element to move away from said first mentioned means substantially immediately following said detecting movement, said first mentioned means upon the frame being mounted directly upon the bar and having a vertical movement, and means for locking the first mentioned means in fixed position when the detector bar is locked.

9. In a warp stop motion for looms, the combination with a heddle frame carrying a series of heddles, of a detector bar movable with the frame and mounted for detecting movement thereon, contact means positioned adjacent said heddle frame adapted to be engaged as the heddle frame moves to impart to said bar a rocking detecting movement, means movable with said frame for engaging said contact means to rock the bar and being pivotally movable upon engagement with said contact means, means for supporting said contact means whereby the latter may move away from said engaging means on the frame substantially im-

mediately following said detecting movement of the bar, and means for stopping the loom when said bar is locked following its detecting movement.

- 5 10. In a warp stop motion for looms, the combination with a heddle frame carrying a series of heddles, of a detector bar movable with the frame and mounted for detecting movement thereon, contact means positioned adjacent said heddle frame adapted to be engaged as the heddle frame moves to impart to said bar a rocking detecting movement, means movable with said frame and pivotally mounted on an axis other than the 15 axis of said bar for engaging said contact means to rock the bar upon contact with said last mentioned contact means, said frame carried means being pivotally movable upon engagement with said contact means, means 20 for supporting said contact means whereby the latter may move away from said engaging means on said frame substantially immediately following said detecting movement of the bar, and means for stopping the 25 loom when said bar is locked following its detecting movement.

11. In a warp stop motion for looms, a heddle frame having a series of heddles, a detector bar mounted in said frame and having a rocking detector movement thereon, a pivoted finger on said heddle frame pivotally movable to impart detecting movement to said bar, means for locking said pivoted finger against movement when said detector bar is locked by a fallen heddle, means engageable as the heddle frame moves to rock said bar and move said finger, and means engageable by said finger to stop the loom as the heddle frame moves.

- 40 12. In a warp stop motion for looms, a heddle frame having a series of heddles, a detector bar mounted in said frame and having a rocking detector movement thereon, a pivoted finger on said heddle frame pivotally movable to impart detecting movement to said bar, means for locking said pivoted finger against movement when said detector bar is locked by a fallen heddle, means engageable by said finger as the heddle frame 45 moves to rock said bar, means engageable by said finger to stop the loom as the heddle frame moves following locking of the bar, and means for supporting said bar rocking means to permit the latter to move vertically away from said bar substantially immediately following said detecting movement thereof.

13. In a warp stop motion for looms, the combination with a heddle frame having a series of heddles, a detector bar mounted on said frame having a rocking detecting movement, a contact finger pivotally mounted for a pivotal movement independently of the bar, but being adapted during at 60 least a portion of its movement to impart

to the bar a detecting movement, means engageable as the heddle frame moves to move said finger on said bar and to impart a detecting movement to the bar, and means for locking said finger against pivotal movement when the bar is locked by a fallen heddle.

70 14. A warp-stop motion having in combination a plurality of drop wires arranged in parallel banks, oscillating detector bars for said drop wires, link means connecting said detector bars for simultaneous oscillation, and means for adjusting the arc of oscillation of said detector bars through said link means.

75 15. A warp stop motion having in combination a plurality of drop wires arranged in parallel banks, oscillating detector bars for said drop wires, link means connecting said detector bars for simultaneous oscillation, means for adjusting the arc of oscillation of said detector bars through said link means, said adjusting means being adapted to vary the effective length of said link means between the detector bars.

80 16. In a warp stop motion for looms, a harness frame having a detector bar therein, and a plurality of heddles associated therewith, movable means carried by the harness frame for imparting a detecting movement to said bar as the heddle frame moves in one direction, contact means on the loom adapted to be engaged by said first mentioned means as the heddle frame moves in said direction, said two means being arranged so as to be disengaged substantially immediately following the detecting movement of said link and before the heddle frame moves in a reverse direction, whereby to permit the detector bar to move reversely after its detecting movement before the harness frame moves in the opposite direction.

90 17. In a warp stop motion for looms, a harness frame having an oscillatory detector bar therein, and a plurality of heddles associated therewith, movable means carried by the harness frame for imparting an oscillatory detecting movement in one direction to said bar as the heddle frame 95 moves downwardly, contact means on the loom adapted to be engaged by said first mentioned means as the heddle frame moves downwardly, said two means being arranged so as to be disengaged substantially immediately following the detecting movement of said link and before the heddle frame moves upwardly, whereby to permit the detector bar to move reversely after its detecting movement before the harness frame moves upwardly.

100 18. In a warp stop motion for looms, the combination with a vertically and bodily movable detector bar, of a contact element 105 to impart a detecting motion to said bar

as it moves vertically in one direction, and means for freeing said detector bar of said contact element by movement of the latter away from the bar substantially immediately following its detecting movement and substantially before the bar begins to move in the opposite direction, said last mentioned means being independent of the loom lay and comprising a cam and a member movable thereby, said member having connections with said contact element.

19. In a warp stop motion for looms, the combination with a heddle frame having a series of heddles, of a substantially horizontally disposed detector bar movable with the frame and having the detecting movement thereon, contact means engageable as the heddle frame moves in one direction to impart to the bar a detecting movement, said contact means having a normal detecting position and being movable away therefrom substantially immediately following detecting movement of the detector bar and substantially before the heddle frame moves 25 in the opposite direction, whereby to disengage the contact means from the detector bar, and means for operating said contact element to carry it toward and from its contact position, said means being independent of the loom lay.

20. In a warp stop motion for looms, the combination with a heddle frame having a series of heddles, of a substantially horizontally disposed detector bar movable with the frame and having the detecting movement thereon, contact means engageable as the heddle frame moves in one direction to impart to the bar a detecting movement, said contact means having a normal detecting position and being movable away therefrom substantially immediately following detecting movement of the detector bar and before the heddle frame moves in the opposite direction, whereby to disengage the contact means from the detector bar, and means for operating said contact element to carry it toward and from its contact position, said means being independent of the loom lay and comprising a rotary cam, and a member movable by said cam and having connections with said contact element.

21. In a warp stop motion for looms, and in combination with the heddle frame and its said forming heddles, a detector bar carried by the frame and having a detecting movement therein, a finger carried by the frame and movable thereon about an axis other than the bar, said finger being adapted upon movement to impart a detecting movement to the bar, a contact element engageable by said finger as the heddle frame moves in one direction to impart movement to the finger and detector bar, said contact element having a normal contact position and being movable away therefrom

substantially immediately following detecting movement of the bar and before the heddle frame moves in the opposite direction, and means for actuating said contact element to carry it toward and from its contacting position, said means being independent of the loom lay.

22. In a warp stop motion for looms, and in combination with the heddle frame and its said forming heddles, a detector bar carried by the frame and having a detecting movement therein, a movable finger carried by the frame and adapted upon movement to impart a detecting movement to the bar, a contact element engageable by said finger as the heddle frame moves in one direction to impart movement to the finger and detector bar, said contact element having a normal contact position and being movable away therefrom substantially immediately following detecting movement of the bar, and substantially before the heddle frame moves in the opposite direction, and means for actuating said contact element to carry it toward and from its contacting position, said means being independent of the loom lay and comprising a rotary cam element, and a member movable thereby, said member having connections with said contact element.

23. A warp stop motion for looms, as specified in claim 21, said motion comprising a second contact element engageable upon upward movement of the harness frame and having connections for stopping the loom only when the detector bar is locked.

24. A warp stop motion for looms, as specified in claim 22, said motion comprising a second contact element engageable upon upward movement of the harness frame and having connections for stopping the loom only when the detector bar is locked.

25. In a warp stop motion for looms and in combination with the lay, heddle frame and its shed forming heddles, a detector bar having a detecting movement, a contact element adjacent the frame and lay adapted to impart a detecting movement to said bar, said contact element being yieldably movable in a substantially horizontal plane.

26. In a warp stop motion for looms and in combination with the lay, heddle frame and its shed forming heddles, a detector bar having a detecting movement in said frame, a contact element adjacent the frame and lay adapted to impart a detecting movement to said bar as the heddle frame moves, said contact element being yieldably movable in a substantially horizontal plane and away from the lay whereby to prevent injury to the hand or other part interposed between the contact and the lay.

27. In a warp stop motion for looms and in combination with the lay, heddle frame and its shed forming heddles, a detector bar

having a detecting movement, a contact finger associated with said detector bar, a contact element mounted adjacent the lay and adapted to be engaged by said contact finger, and means for yieldingly restraining said contact element against horizontal movement whereby the latter may yield horizontally upon interposition of the hand or other part of an operator between the contact and the lay.

28. In a warp stop motion for looms and in combination with the heddle frame and its shed forming heddles, a detector bar having a detecting movement and mounted in said frame, movable means on the loom adapted to be actuated when the detector bar is locked to stop the loom, a dagger, means operatively connecting said contact element with said dagger whereby the latter is moved upon actuation of said contact element, said means having a connection with said dagger of a character adapted to cause movement of the latter a predetermined and invariable distance regardless of variations in the distance of movement of said contact element when the detector bar is locked.

29. In a warp stop motion for looms and in combination with the heddle frame and its shed forming heddles, a detector bar mounted in said heddle frame and having a detecting movement, a contact finger movable independently of the detector bar and adapted to impart a detecting movement to the latter, contact means mounted on the loom adapted to be engaged by the contact finger upon movement of the heddle frame in one direction to impart a detecting movement to said bar, and means other than upward movement of the heddle frame for insuring discontinuance of moving pressure upon said detector bar from said contact element upon completion of the detecting movement of the bar regardless of variations in the movement of the heddle frame.

30. In a warp stop motion for looms and in combination with the heddle frame and its shed forming heddles, a detector bar mounted in said heddle frame and having a detecting movement, a contact finger operatively associated with said bar to move the latter and movable independently of the detector bar about an axis other than the detector bar axis, a contact element mounted on the loom adjacent said heddle frame adapted to be engaged by said finger upon movement of the heddle frame in one direction to impart a detecting movement to said bar, and means other than upward movement of the heddle frame operative upon completion of the detecting movement of the bar through said finger to relieve the detector bar from moving pressure.

31. In a warp stop motion for looms and in combination with the heddle frame and

its shed forming heddles, a detector bar mounted in said heddle frame and having a detecting movement, a contact finger movable with said frame operatively associated with said bar to move the latter and having a pivotal movement about an axis other than the axis of said bar, a contact element mounted on the loom adjacent said heddle frame adapted to be engaged by said finger upon movement of the heddle frame in one direction to impart a detecting movement to said bar, and means other than the upward movement of the heddle frame operative upon completion of the detecting movement of the bar through said finger to relieve the detector bar from moving pressure.

32. In a warp stop motion for looms and in combination with the heddle frame and its shed forming heddles, a detector bar mounted in said heddle frame and having a detecting movement, a contact finger movable with said frame operatively associated with said bar to move the latter and having a pivotal movement about an axis other than the axis of said bar, said finger axis being angularly disposed with relation to the bar axis, a contact element mounted on the loom adjacent said heddle frame adapted to be engaged by said finger upon movement of the heddle frame in one direction to impart a detecting movement to said bar, and means other than the upward movement of the heddle frame operative upon completion of the detecting movement of the bar through said finger to relieve the detector bar from moving pressure.

33. In a warp stop motion for looms and in combination with the heddle frame and its shed forming heddles, a detector bar mounted in said heddle frame and having a detecting movement, contact means mounted on the loom adapted to be engaged upon movement of the heddle frame in one direction to impart a detecting movement to said bar, and means other than upward movement of the heddle frame for insuring discontinuance of increase in pressure upon said detector bar upon completion of its detecting movement, said last mentioned means comprising mechanism for moving said contact element away from the detector bar upon completion of its detecting movement.

In testimony whereof we have hereunto set our hands.

JOSEPH G. MENZER.
HARRY E. KHOURY.
